(57) **CLAIM**

The ornamental design for a rail cleaner, as shown and described.

DESCRIPTION

FIG. 1 is a perspective view of a rail cleaner depicting a new design;

FIG. 2 is another perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The broken line portion of the figure drawings is included to show unclaimed subject matter only and forms no part of the claimed designs. Moreover, the rail section shown in broken lines is intended to provide environmental context and forms no part of the claimed designs.
